UNITED STATES PATENT OFFICE

HARRY C. LYONS, OF MOUNT VERNON, NEW YORK

SMOKE SEPARATOR

Application filed April 17, 1928. Serial No. 270,638.

My invention relates to a method of and apparatus for separating certain constituents of smoke and the like.

In the products issuing from a smoke-stack or chimney, and ordinarily referred to as "smoke", there is often a considerable quantity of substantially pure carbon in the form of soot, and this soot, if permitted to escape, not only tends to pollute the atmosphere, but 10 is lost for all practical commercial purposes.

It is my object to provide an improved method of and apparatus for separating and collecting soot and the like from smoke or other gases.

15 Briefly stated, in the preferred form of the invention, I position a smoke collector, which may be in the form of an endless belt, in the path of a current of smoke issuing from a smoke-stack or the like, and I preferably moisten the smoke collector so as to facilitate the adherence of soot particles and the like thereto. Particles of soot and the like 20 on coming in contact with the collector adhere thereto, and the adhering particles are later removed and collected. This removal may be effected for example by means of a suitable 25 scraper, or by means of washing, or both.

In the drawings which show, for illustrative purposes only, preferred forms of the 30 invention—

Fig. 1 is a partially diagrammatic sectional view of a smoke separator for carrying out my process, and illustrative of my invention;

35 Fig. 2 is a view similar to Fig. 1, but illustrating a modification.

In said drawings, 5 indicates a smoke-stack, chimney, or other smoke conduit. Above the chimney or at any point in the current of smoke, I position a smoke collector, which 40 may be in the form of a belt 6. In the form illustrated, the belt 6 is trained over suitable guide rollers and is positioned horizontally. The positioning of the belt may, however, be varied, and in some cases it may be desirable 45 to incline the belt substantially.

The belt 6 or other form of collector is preferably moistened with water or other liquid to facilitate and induce the adherence of soot particles and the like thereto. The soot particles on coming in contact with the moistened

belt adhere thereto, and these particles are later removed from the belt and collected. In the form shown, the belt 6 passes in engagement with a scraper 7 positioned in a collecting pan or tray 8. The scraped off soot particles may drop into the tray and be removed from time to time. I prefer to partially fill the tank or tray 8 with water or other moistening liquid, so that the belt may be caused to pass through the liquid. In some cases, 55 I may omit the scraper 7 entirely, and rely upon the passage of the belt through the liquid for the removal of the soot particles as well as for moistening the belt. It is possible, also, instead of having the belt pass through a body of water, to spray water onto the belt. In the form shown wherein the belt 6 is an endless one, it is trained over suitable pulleys or rollers, as illustrated, to cause the belt to move in the desired course. Any 60 suitable means, such as a small motor 9, may be employed for driving the belt.

65 The parts heretofore described may all be mounted upon a suitable framework 10, which may be supported by any suitable base, for example a smoke-stack or chimney 5. The framework 10 is preferably adjustably mounted upon its support so that the smoke collector, or specifically the belt, may be positioned at just the desired distance from the 70 point of issuance of the smoke from the smoke-stack.

75 In the modification illustrated in Fig. 2, the framework 11 supports substantially the same elements as have been described in connection with Fig. 1. In the form shown in Fig. 2, however, the belt 12 is substantially horizontally disposed at the zone 13, while the parts of the belt designated 14 are inclined downwardly. This disposition of the belt provides a tortuous path for the smoke, and presents in general a larger and more effective area for the smoke to contact with. As shown in Fig. 2, a soot remover such as 80 the scraper 15 may be provided, and it need not be positioned in the tank 8, though if desired an additional scraper 7 may be provided the same as in that form shown in Fig. 1. If a soot remover 15 is positioned outside 85 of the tank or pan 8, I may employ a collec- 90

100

tion box 16 for the removed soot. In connection with Fig. 2, I may also partially fill the tray 8 with water or other liquid for removing or assisting in the removal of soot which 5 has collected on the belt, as well as for moistening the belt. Any means such as the motor 9 may drive the belt 12.

In general, it is my purpose to collect soot upon any suitable medium and thereafter re-10 move the soot by any suitable means such as the scrapers illustrated, or by washing the belt, or by both or other methods, and I do not wish to be confined to any particular apparatus except as may be required by the 15 claims herein. Many changes and modifications may be made within the scope of the invention as defined in the appended claims.

I claim:

1. In a smoke separator, a framework ex-20 tending above the substantially vertical outlet of a chimney, an endless belt carried by said framework, said endless belt having a substantially horizontal portion just above the vertical chimney outlet, a tank for con-25 taining liquid carried by said framework above the horizontal portion of said endless belt, and means for guiding said endless belt through a body of liquid in said tank.

2. In a smoke separator, a framework to be 30 positioned above the substantially vertical outlet of a chimney, an endless belt carried by said framework, said endless belt being guided above the substantially vertical outlet of said chimney and having portions guided 35 downwardly so as to partially embrace the space at the side of the chimney adjacent the outlet, a tank for holding liquid carried by said framework above that portion of said endless belt which is trained just above the 40 chimney outlet, and means for guiding said endless belt through the body of liquid in said tank.

HARRY C. LYONS.
